UNITED STATES PATENT OFFICE.

FREDERICK H. BUSBY, OF SAN FRANCISCO, CALIFORNIA.

GLOVE.

SPECIFICATION forming part of Letters Patent No. 745,150, dated November 24, 1903.

Application filed February 16, 1903. Serial No. 143,465. (No model.)

To all whom it may concern:

Be it known that I, FREDERICK H. BUSBY, a citizen of the United States, residing in the city and county of San Francisco, State of California, have invented certain new and useful Improvements in Gloves; and I do hereby declare the following to be a full, clear, and exact description of the same.

My invention relates to the class of gloves; and it consists in the novel construction and relative arrangement of the parts or portions thereof, which I shall hereinafter describe.

The object of my invention is to provide a strong, well-fitting, and comfortable glove, with due regard to economy in cutting, said object being obtained by such patterns as will give when united a glove in which the entire thumb is integral with the main portion, leaving no seams of any kind in the palm of the glove, the thumb springing integrally from the palm in the most natural and favorable position for freedom and fit and giving the maximum strength to resist all strains.

Referring to the accompanying drawings, Figure 1 is a front view of my glove. Fig. 2 is a back view of same. Fig. 3 is a view of the main pattern or trunk forming the larger portion of the glove, including the integral thumb, and showing also in dotted lines the stretched point a^3 , underlying the upper part of the thumb portion. Fig. 4 is a broken or partial view of the trunk of Fig. 3 reversed to show the stretched point a^3 in full. Fig. 5 is a view of the fourchette of the second finger. Fig. 6 is a view of the fourchette of the third finger. Fig. 7 is a view of the front wrist-gore.

In the glove shown in Figs. 1 and 2 a single piece or trunk A forms the entire front a of the palm and wrist, with the exception of a gore in the wrist, the entire thumb a' , with its ball and wrist extension, both front and back, the entire first and fourth fingers 1 and 4, the fronts 2 and 3 of the second and third fingers, and back a^2 of the glove on the fourth-finger side. The remainder of the back of the glove is formed by the fourchettes B and C of the second and third fingers, respectively. The remainder or excepted part of the front of the glove—to wit, the wrist—is formed by a gore D, which is originally a single piece,

but when the glove is completed is, as shown, divided by the wrist-opening d.

To better understand the parts of the glove, I refer now to Figs. 3, 4, 5, 6, and 7, which show the patterns or shapes of these parts before they are united. In Fig. 3 the main pattern or piece is designated by A, its several portions being correspondingly lettered and numbered to those of the glove—to wit, the palm a , the thumb a' , the first and fourth fingers 1 and 4, the fronts 2 and 3 of the second and third fingers, and the fourth-finger side of the back a^2 . The fourchettes B and C of the second and third fingers 2 and 3 are shown in Figs. 5 and 6, and the wrist-gore D is shown complete in Fig. 7. Now it will be seen that when the main piece or trunk A is bent or folded to have its several seams sewed up the front of the palm of the glove, as shown in Fig. 1, has not a single seam in it, and the thumb forms an integral part of it, thus avoiding the usual construction of a separate thumb in whole or in part and the usual seam bounding the ball of the thumb, as when the thumb is set into the usual thumb-gouge. It will further be seen by Fig. 2 that the only seam in the back is the short seam y y , which extends from the base of the thumb connection with the first finger across to the seam b b , which unites the main piece to the second-finger fourchette B, said seam y y extending diagonally downwardly and in line with and continuing, in fact, the seam of the thumb itself. Finally, by reference to Fig. 1, it will be seen that the seams d d' , which unite the gore D to the main piece, are well down on the wrist of the glove. Thus I am enabled to secure the main object of my invention, which is to form the entire thumb integral with the main part of the glove and to avoid any seams in the palm. There is in my glove, therefore, no seam on the palm to strain and open, as is the case where the thumb is in whole or in part a separate piece and is let into a thumb-gouge. The seams d d' in the front being on the wrist are not subject to injurious strain. My construction also gives greater freedom to the thumb and to the whole hand, makes a good fit, gives durability to the glove, and results in economy in cutting.

In practice there is a further and very es-

ential point to be noticed in the construction of the main piece A, with regard to the best position of the seam $y'y$, which when the glove is sewed up is the only seam required 5 to unite the thumb portion to the rest of the trunk A. This seam is formed by the union of the edge y' , Figs. 3 and 4, at the base of the first finger with the edge y^2 , Fig. 3, on one side of the wrist or top below the thumb. 10 If the edge y' at the base of the first finger be cut in straight as the continuation of the thumb cut and nothing further is done, the resulting seam $y'y$ will pass directly and substantially at right angles over the knuckle of 15 the first finger. This is not the best disposition of this seam, as it is both inconvenient to the finger and is subject to the full strain of the most powerful knuckle. If the edge y' were cut from a little above at a downward 20 inclination to meet the cut of the thumb, the resulting seam would extend at an upward inclination in front of the knuckle. This direction of the seam, while perhaps better than the straight one, is still not desirable, as it is un- 25 slightly. The best direction for the seam $y'y$ is that shown in Fig. 2, wherein it extends or inclines diagonally downwardly below the knuckle, thus giving entire freedom with minimum strain; but as this direction neces- 30 sarily implies an undercutting of the edge y' , which, as shown in Fig. 3, lies considerably under the thumb, being formed by a positively-projecting point a^3 of material integral with the rest of the piece, it would seem at 35 first glance impossible to cut out such a pattern; but the capability of leather to stretch furnishes the solution. The underlying point a^3 is stretched to its shape after a preliminary straight cut, and thereby forms the pro- 40 jecting point a^3 , as shown in full in the reversed Fig. 4, said point having inclined edge y' , which is necessary to give the required downward inclination to seam $y'y$. It will be noted also that the thumb portion of the pattern of 45 Fig. 3 is not cut at exactly right angles to the remainder of the pattern, but is slightly downwardly inclined thereto. This necessitates the lower edge of the wrist or top of the glove to be cut parallel to the thumb inclina- 50 tion, whereby when folded the top will be square and the thumb will be given a more natural position with relation to the glove.

The gore D of Fig. 7 is a single piece at first, and on account of the incline of the thumb 55 and top said gore is an unequal-sided triangle. It is seamed into the glove as a whole and is subsequently cut on the line d^2 , Fig. 7, to form the wrist-opening d , Fig. 1, the cut of said opening being continued, as shown, beyond 60 the apex of the gore-seams $d'd'$, so that said

cut enters the strong material of the glove and does not terminate in a union of seams.

Having thus described my invention, what I claim as new, and desire to secure by Letters Patent, is—

65

1. In a glove, a main portion formed from a trunk having a thumb integral therewith, the trunk being separated along the upper edge of the thumb and base of the first finger and the base of said finger having a point 70 overlapping the thumb, the inner edge of said point inclining upwardly toward the interior of the trunk, said trunk having also a free edge below the thumb adapted to unite with the inclined edge of the point to join the 75 thumb by a seam in the back extending diagonally downwardly across the base of the first finger below the knuckle.

2. A glove consisting of a main portion formed from a trunk having a thumb integral 80 therewith, the trunk being separated along the upper edge of the thumb and base of the first finger and the base of said finger having a point overlapping the thumb, the inner edge of said point inclining upwardly toward the 85 interior of the trunk, said trunk having also a free edge below the thumb adapted to unite with the inclined edge of the point to join the thumb by a seam in the back extending diagonally downwardly across the base of the 90 first finger below the knuckle, suitable fourchettes in the back, and a gore in the front wrist.

3. A glove consisting of an integral main portion forming the palm, the thumb with its 95 wrist extension, the first and fourth fingers with the wrist extension of said fourth finger, and the fronts of the second and third fingers, the thumb of said main portion being separated along its upper edge from the 100 base of the first finger and the base of said finger having a point overlapping the thumb, the inner edge of said point inclining upwardly toward the interior of said main portion, said main portion having also a free 105 edge below the thumb adapted to unite with the inclined edge of the point to join the thumb by a seam in the back extending diagonally downwardly across the base of the first finger below the knuckle, fourchettes 110 forming the backs of the second and third fingers and the wrist extensions, and a gore in the front wrist to complete the top.

In witness whereof I have hereunto set my hand.

FREDERICK H. BUSBY.
